UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed July 29, 1927. Serial No. 209,316.

This invention relates principally to car roofs of the all-steel flexible type wherein the metal roof sheets extend from eaves to eaves of the car between carlines and are 5 loosely connected along their adjacent side margins by weatherproofing seam caps that are secured to the car substructure and thus serve to hold the roof sheets down on the car. The principal object of the present invention is to provide improved means for 10 securing an insulating lining to the underside of roofs of the above type and thereby prevent sweating or condensation of moisture on the undersurfaces of the roof sheets 15 and carlines. Other objects are simplicity and cheapness of construction and ease of application. The invention consists in the parts and in the combinations and arrangements of parts hereinafter described and 20 claimed.

The accompanying drawing, which forms part of the specification and wherein like symbols refer to like parts wherever they occur.

25 Fig. 1 is a plan view of a portion of a radial all-steel flexible car roof equipped with an insulating lining embodying my invention, portions of the metal roof covering being shown broken away to more clearly 30 illustrate the invention.

Fig. 2 is an enlarged transverse section through one-half the roof, the section being taken between seams on the line 2—2 in Fig. 1.

35 Fig. 3 is an enlarged vertical cross-section taken through one of the seams at the ridge on the line 3—3 in Fig. 2.

Fig. 4 is a similar cross-section through said seam intermediate the rigid eaves on 40 the line 4—4 in Fig. 2.

Fig. 5 is a transverse cross-section similar to Fig. 2 illustrating a modified construction of roof lining.

Fig. 6 is a vertical cross-section at the 45 ridge on the line 6—6 in Fig. 5.

Fig. 7 is a vertical section similar to Figs. 2 and 5 showing another modification of roof lining in connection with a car having Z-bar side plates; and

Fig. 8 is a vertical cross-section through the roof seam on line 8—8 in Fig. 7.

Referring to Figs. 1 to 4, inclusive, of the accompanying drawings, my invention is shown in connection with the radial all-steel flexible car roof comprising angle bar side plates 10 that are connected by carlines 11 of substantially inverted channel-shaped section with outwardly projecting base flanges 12 at the bottoms of their side walls. The angle bar side plates 10 are preferably 55 arranged with one flange vertical and with the other flange disposed uppermost and extending outwardly horizontally. The eaves end portions of the carlines rest flatwise on the outstanding upper flanges of the side 60 plates and have their flanges riveted or otherwise rigidly secured thereto.

Full length metal roof sheets 13 of relatively light gage extend from eaves to eaves between carlines and are supported at their 70 eaves ends on wooden filler strips 14 which extend from carline to carline and are bolted or otherwise rigidly secured to the outstanding top flanges of the side plates 10. The roof sheets 13 are supported on the filler 75 strips 14 above the plane of the lateral base flanges 12 of the carlines 11 and have upwardly offset marginal portions 15 that are

inclined upwardly and terminate in side 80 marginal flanges 16 that extend from end to end of the sheets and are normally spaced away from the sides of the body portions of the carlines. The roof sheets 13 are also provided at their eaves ends with depending flanges 17 that overhang and are normally spaced from the outer edges of the 85 wooden filler strips 14 and the side plates 10.

Weatherproofing members in the form of inverted channel-shaped seam covers or caps A straddle adjacent side marginal flanges 16 of the roof sheets and portions of the carlines located therebetween, the inside width of the seam covers being sufficient to leave a space between each side wall thereof and said adjacent marginal seam flanges 16. The webs 90 or tops of the channel-shaped seam covers bear flatwise against the webs or tops of the channel-shaped carlines 11 and are riveted or

otherwise rigidly secured thereto. The channel-shaped seam covers are provided along the lower edges of their side walls with outstanding base flanges 18 that rest or bear flatwise on the inclined side marginal portions 15 of adjacent roof sheets and thus serve to hold said sheets down on the car. The eaves end portions of the seam caps are provided with depending eaves flanges 19 which cover the open ends of the carlines and the eaves corners of adjacent sheets and are normally spaced away from the latter. The transverse seam caps A are preferably made in three sections: namely, duplicate end members or sections 20 which extend from the eaves to points adjacent to the ridge, and a single intermediate or ridge section 21, which overlaps the ridge end portions of the two end sections for a suitable distance on each side of the ridge. The ridge section of each seam cap is pressed outwardly adjacent to each end, as at 22, to provide space between the overlapping portions of the ridge and end sections for strips of tar paper or other suitable material 23 which is dipped in paint before application.

Running boards 24 extend longitudinally from the car at the ridge and are supported on the lateral top flanges of Z-bar running board saddles 25 whose lateral base flanges rest on the ridge sections 20 of the seam caps A and are rigidly secured thereto by the rivets that secure the ridge portions of the caps to the carlines.

In order to insulate the above roof against heat and to eliminate sweating or condensation of moisture on the undersurface of the roof sheets and carlines, said roof is provided with an insulating lining B which extends from side plate to side plate and from end to end of the car. As shown in Figs. 1 to 4, inclusive, said lining comprises matched or tongue and groove sheathing boards 26 which extend longitudinally of the car beneath the carlines and roof sheets and insulates the underside of the entire roof. The sheathing boards are long enough to span the spaces between two or more carlines; and each board is preferably bolted or otherwise rigidly secured to the undersides of one of the outstanding base flanges 12 of every other carline 11 by bolts 27.

As stated above, the roof sheets are supported on the wooden eaves filler strips 14 above the plane of the lateral base flanges 12 of the carlines 11 and the roof lining B is disposed beneath the carlines, thereby forming a dead air space 28 between said roof sheets and said lining which serves as a heat insulator. As shown in the drawing, the sheets are supported intermediate their eaves ends by means of wooden filler strips 29, which extend longitudinally of the car between carlines and rest on and are nailed to the roof lining. The strips 29 prevent

sagging of the sheets between side plates by reducing the span which the sheets have to bridge, thereby increasing the load carrying capacity of said sheets, maintaining a heat insulating space of uniform depth between 70 the sheets and the roof lining B.

Among the advantages of the above construction are its great simplicity and cheapness and the ease with which it may be applied to or removed from the roof after it 75 has been placed on the car. It is particularly noted that the above construction forms a continuous insulating lining, beneath the roof sheets and the carlines from eaves to eaves and from end to end of the car. 80

The construction shown in Figs. 5 and 6 has the same arrangement of side plates, carlines and seam covers; but the lining boards 30 extend transversely of the car and are supported at the ridge on a ridge pole 31, intermediate the ridge and eaves on purlins 32, and at the eaves in the rabbeted inner edges of wooden filler strips 33 which rest on the side plates. As shown in the drawing, the roof sheets are spaced above the roof lining and carlines, at the ridge, at the eaves, and intermediate the ridge and eaves by filler strips 33^a, which are secured to the tops of the ridge pole 31, purlins 32 and eaves strips 33 and extend longitudinally 85 thereof between carlines. The ridge pole and purlins are bolted to the undersides of the base flanges of the carlines; and the lining boards 30 are arranged in two panels on opposite sides of the ridge, the boards 100 which span the spaces between the ridge pole 31 and purlins 32 being disposed with their ends in abutting relation to the spacing strips supported thereon, and the boards which span the spaces between the purlins 105 and the eaves strips 33 being disposed with their ends in abutting relation to the spacing strips on the purlins and said eaves strips. 110

Figs. 7 and 8 show a construction wherein the roof sheets are supported at the eaves on a filler strip 34, which rests on the horizontal web of Z-bar side plate 35 and is bolted to the upstanding inner flange thereof. The sheets are supported intermediate their eaves ends on a ridge pole 36 and purlins 37 bolted 115 to the base flanges 12 of the carlines 11 and the insulating lining comprises sheathing boards 38, which extend longitudinally of the car between the ridge pole 36 and purlins 37 and between the latter and the side plates 120 and are nailed or otherwise secured to the bottom surfaces of wooden filler strips 38 that fit within the downwardly opening channels of the inverted channel-shaped carlines 11 and are bolted thereto. The carline fillers 38 extend below the lateral flanges 125 12 of the carlines 11 and thus serve to space the insulating lining below the body of the sheets. As shown in Fig. 7, the carlines 11 are secured to said plate 35 by angle-shaped 130

carline brackets 39, having one flange bolted flatwise to the undersides of the carlines and having the other flange extending downwardly and riveted flatwise to the outer face 5 of the upstanding inner flange of the side plate. With this arrangement, the carline fillers or nailing strips 38 terminate short of the carline brackets 39; and the lining boards which extend beneath the carline 10 brackets are preferably bolted to the underside of said brackets, the bolts extending through said bracket and the base flanges of the carlines. As the carline filler strips 38 are primarily intended as nailing strips for 15 supporting the lining between the ridge pole and purlins and between the latter and the carline brackets, said strips are preferably made in four sections, the inner sections extending from the ridge and terminating 20 short of the purlins and the outer sections extending between the purlins and the carline brackets and terminating short thereof.

This invention is not limited to the precise shapes and arrangements of parts shown 25 and described.

What I claim is:

1. A car roof comprising side plates connected by metal carlines, metal roof sheets movably arranged between carlines and supported by said side plates, and an insulating lining for said roof, said lining covering the undersides of said carlines and said roof 30 sheets and being provided with means for supporting said sheets above said lining, 35 thereby forming dead air spaces between said sheets and said lining.

2. A car roof comprising side plates connected by metal carlines, and an insulating lining comprising sheathing boards extending 40 longitudinally of the car between side plates and removably secured to the undersides of said carlines, metal roof sheets located above said sheathing boards and extending from side plate to side plate between 45 carlines, and spacing strips resting on the sheathing boards between carlines for supporting said roof sheets above said sheathing boards.

3. A car roof comprising side plates connected by metal carlines, metal roof sheets extending from side plate to side plate between carlines, and an insulating lining for 50 said roof sheets and carlines, said lining comprising sheathing boards extending longitudinally of the car beneath the carlines and roof sheets, said sheathing boards being suspended from said carlines, some of said sheathing boards extending above the other sheathing boards to provide spaced supports 55 for said roof sheets.

4. A car roof comprising side plates connected by metal carlines, metal roof sheets extending from side plate to side plate between carlines, a wooden ridge pole and 60 purlins secured to the undersides of said car-

lines and supporting said sheets intermediate said side plates, and an insulating lining for said roof sheets and carlines, said lining comprising sheathing boards extending longitudinally of the car beneath the 70 carlines and roof sheets between the ridge pole and purlins and the latter and the side plates, said sheathing boards being suspended from said carlines, said ridge pole and purlins extending above the sheathing 75 boards, whereby said sheathing boards are spaced below said roof sheets to form a dead air space therebetween.

5. A car roof comprising side plates connected by metal carlines, metal roof sheets 80 extending from side plate to side plate between the carlines, a ridge pole and purlins secured to the undersides of said carlines and supporting said sheets intermediate the side plates, wooden filler strips secured to 85 said carlines, and an insulating lining for said carlines and said roof sheets, said lining comprising sheathing boards extending longitudinally of the car beneath the carlines and roof sheets between the ridge pole 90 and purlins and the latter and the side plates, said sheathing boards being secured to the undersides of said filler strips, said filler strips extending below the bodies of 95 the roof sheets, thereby forming dead air spaces between the sheets and the insulating lining.

6. A car roof comprising side plates connected by metal inverted channel-shaped carlines with outstanding base flanges, a 100 ridge pole and purlins extending longitudinally of the car beneath the carlines intermediate the side plates and rigidly secured to said carlines, metal roof sheets extending from eaves to eaves of the car between carlines and supported on the ridge pole, purlins and side plates, wooden filler strips secured within the inverted channel portions of said carlines and extending below the roof sheets, and an insulating lining for 105 said roof sheets and carlines, said lining comprising sheathing boards extending longitudinally of the car beneath the carlines and roof sheets between the ridge pole and the purlins and between the latter and the 110 side plates and secured to the undersides of said filler strips.

7. A car roof comprising side plates connected by metal carlines, metal roof sheets extending from side plate to side plate between 120 carlines, a wooden ridge pole and purlins rigidly secured to the undersides of the carlines and an insulating lining located beneath said roof sheets, said lining comprising sheathing boards spanning the spaces 125 between the ridge pole and purlins, and the latter and the side plates, said boards being spaced below the tops of the ridge pole and purlins.

8. A car roof comprising side plates con-

nected by metal carlines, metal roof sheets extending from side plate to side plate between carlines, a ridge pole and purlins rigidly secured to the undersides of the carlines, an insulating lining located beneath said roof sheets, said lining comprising sheathing boards spanning the spaces between the ridge pole and purlins and the

latter and the side plates, and spacing strips resting on said ridge pole, and purlins 10 and on the eaves ends of said sheathing boards for spacing said roof sheets above said sheathing boards.

Signed at New Kensington, Pennsylvania, this 25th day of July, 1927.

CHARLES DAVID BONSALL.
